UNITED STATES PATENT OFFICE

170,336

PLATE OR THE LIKE

Gordon Parker, Alliance, and Beatrice L. Miller,
Cleveland, Ohio, assignors to Royal China Inc.,
Sebring, Ohio, a corporation of Ohio

Application March 20, 1953, Serial No. 24,146

Term of patent 14 years

(Cl. D44—15)

To all whom it may concern:

Be it known that we, Gordon Parker and Beatrice L. Miller, citizens of the United States, residing in Alliance, county of Stark, State of Ohio, and Cleveland, county of Cuyahoga, State of Ohio, respectively, have invented a new, original, and ornamental Design for a Plate or the like, of which the following is a specification, reference being had to the accompanying drawing, forming a part thereof.

The figure is a top plan view of a plate or the like, showing our new design. The shape of the plate or the like is of conventional configuration viewed from the side or bottom thereof.

We claim:

The ornamental design for a plate or the like, substantially as shown and described.

GORDON PARKER.
BEATRICE L. MILLER.
